(57) **CLAIM**

The ornamental design for a jump starter as shown and described.

DESCRIPTION

FIG. 1 is a front, right and bottom perspective view of a first embodiment of a jump starter, showing my design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right and bottom perspective view of a second embodiment of the jump starter.

FIG. 10 is a rear, left and top perspective view of the second embodiment of FIG. 9.

FIG. 11 is a front elevation view of the second embodiment of FIG. 9.

FIG. 12 is a rear elevation view of the second embodiment of FIG. 9.

FIG. 13 is a left side elevation view of the second embodiment of FIG. 9.

FIG. 14 is a right side elevation view of the second embodiment of FIG. 9.

FIG. 15 is a top plan view of the second embodiment of FIG. 9; and,

FIG. 16 is a bottom plan view of the second embodiment of FIG. 9.

(Continued)

The dashed broken lines depict portions of the jump starter that form no part of the claimed design. The drawings include a symbolic break in length of the article represented by short dash-long dash broken lines. The appearance of any portion of the article between the break lines forms no part of the claimed design.

1 Claim, 16 Drawing Sheets
